The ornamental design for a horticulture grow light housing, as shown and described.

DESCRIPTION

FIG. 1 is a front bottom view of a horticulture grow light housing showing my new design;

FIG. 2 is a top rear perspective view thereof;

FIG. 3 is a left side view thereof;

FIG. 4 is a right side view thereof;

FIG. 5 is a rear elevation view thereof;

FIG. 6 is a front elevation view thereof;

FIG. 7 is a bottom view thereof; and,

FIG. 8 is top view thereof.

The broken lines in the drawings represent portions of the horticulture grow light housing which form no part of the claimed design.
